UNITED STATES PATENT OFFICE.

HERBERT W. CHENEY, OF MILWAUKEE, WISCONSIN, ASSIGNOR, BY MESNE ASSIGNMENTS, TO ALLIS-CHALMERS MANUFACTURING COMPANY, A CORPORATION OF DELAWARE.

CONTROLLER FOR ELECTRIC MOTORS.

1,125,815.

Specification of Letters Patent.

Patented Jan. 19, 1915.

Application filed December 29, 1909. Serial No. 535,382.

To all whom it may concern:

Be it known that I, HERBERT W. CHENEY, a citizen of the United States, residing at Milwaukee, in the county of Milwaukee and 5 State of Wisconsin, have invented certain new and useful Improvements in Controllers for Electric Motors, of which the following is a full, clear, and exact specification.

10 This invention relates to improvements in operating mechanisms for controllers and particularly for controllers or potential starters utilized for starting induction motors. 15 In controllers generally it is desirable that the drums or movable contact carrying devices be shifted with quick movements to avoid arcing between the fixed and movable contacts. It is also desirable in controllers 20 of certain types, particularly potential starters for induction motors, that the controller drum be movable from a "running" to an "off" position without passing through a "starting" position. Consequently some 25 controllers, such as potential starters, have been so designed that the controller drum can be shifted from an "off" position through one or more "starting" positions to the "running" position and then again 30 to the "off" position by successive movements in a forward direction. However, in controllers of this type it is desirable that the drum be capable of movement in a backward direction from a "starting" position 35 directly to an "off" position, but to avoid danger of injury to the controller in the hands of an inexperienced or careless operator, means should be provided for preventing a movement of the drum in a backward 40 direction from either an "off" position to a "running" position or from a "running" position to a "starting" position.

One of the objects of my invention is the provision of an improved operating mechanism for controllers wherein the controller drum will be shifted with a snap action as it is moved from any position to another.

A further object is the provision of an operating mechanism which will permit the drum to be moved with a quick break or snap action to all the different positions in a forward direction and from a "starting" to an "off" position in a backward direction, but which will prevent the drum being

55 moved in a backward direction from an "off" position to a "running" position or from a "running" position to a "starting" position.

My invention may be briefly summarized as consisting in certain novel details of construction and combinations and arrangements of parts which will be described in the specification and set forth in the appended claims.

In the accompanying drawings wherein I 65 have shown one form of my invention applied to a potential starter, Figure 1 is a side view of the potential starter equipped with my improved operating mechanism, the latter and certain other portions being 70 shown in section. Fig. 2 is an end view of the same with the handles of the starter shown in an "off" position. Fig. 3 is an enlarged sectional view taken along the line 3—3 in Fig. 4 in the direction indicated by 75 arrows through a portion of the operating mechanism and through a portion of the supporting frame of the starter. Fig. 4 is a vertical transverse sectional view of the operating mechanism, the section being taken 80 substantially along the line 4—4 of Fig. 3 looking in the direction indicated by the arrow. Figs. 5 and 6 are diminished front elevations of notched disks forming the ratchet mechanism.

85 Referring now to the figures of the drawings 10 represents a cast metal supporting frame of the potential starter, the upper part of the frame being provided with a sheet metal cover plate 11 which forms a 90 casing in which one or more transformers (not shown) may be mounted, and the lower portion of the frame supporting a sheet metal tank 12 adapted to be filled with oil and to inclose the contact mechanism of the 95 starter. The tank 12 is removably secured to the frame 10 as in the usual manner by suitable members 13, which are pivotally connected to the tank and engage slotted lugs 14 on the lower portion of the frame 10. 100

The frame 10 is provided at one end with a bearing 15 in which is supported a spindle having secured to its inner end a gear 17 which forms part of the driving mechanism of the starter drum and which meshes with 105 a gear 18 mounted on a shaft or stud 19 supported in a depending bracket 20 of the frame. This gear 18 meshes with a suitable

gear 21 at the end of the starter drum 22 mounted on a shaft 23 which is rotatably supported in the lower ends of the bracket 20 and a similar bracket (not shown) at the opposite end of the frame. The drum 22 is provided with series of contacts 24 shown by dotted lines in Fig. 2 which contacts are adapted to engage stationary contact fingers 25, the contact mechanism being inclosed in the oil tank 12. It may be here stated that the drum has six operative positions, two "off" positions, two "starting" positions, and two "running" positions, one "starting" position only being provided in this case between an "off" and a "running" position.

Loosely mounted on the outer end of the shaft 16 so that it may turn relative thereto, is a member 26 having a hub portion 27 which engages the spindle 16 and a disk-like flange 28 surrounding the spindle.

Located between the hub 27 and an outwardly projecting boss forming part of the bearing 15 previously referred to, is a member 29 having a hub 30 which is fixed to the spindle 16 and having a disk-like flange 31 which is parallel to the flange 28 and is spaced a short distance therefrom. The flange 28 of member 26 has secured thereto a pair of operating handles 32 and 33, which, as shown most clearly in Fig. 2, are in alinement with each other.

In Fig. 4 the different operative positions of the handles are indicated by the dot and dash lines designated "off," "starting" and "running", these positions corresponding to the "off," "starting" and "running" positions of the drum 22. It will be understood that the two "off" positions (and also the other like positions) are one hundred and eighty degrees apart.

Surrounding the shaft and located between the flanges 28 and 31 of the members 26 and 29 respectively, is a coil spring 34, the ends 35 and 36 of which are bent inwardly toward the shaft, as shown, and engage a pair of pins 37 and 38 which extend horizontally between the said ends of the spring, the pin 37 being carried by the flange 31 of member 29, and the pin 38 being carried by the flange 28 of member 26. As will be seen, the arrangement of the spring is such that if the operating handles are turned in either direction, the pin 38 which must move with the handles, will because of its engagement with the ends of the spring, turn one end of the spring and increase the tension of the latter if the other end of the spring is held against movement. Consequently the spring will tend to shift in the same direction the pin 37, member 29 and spindle 16.

Secured to the end of the frame 10 by screws 39 and dowel pins 40 are a pair of notched disks or ratchets 41 and 42, these

disks being located side by side adjacent the flange 31 of member 29 and surrounding the spindle 16. Disk 41 is provided with three pairs of equally spaced notches 43 and 43^a, 44 and 44^a, 45 and 45^a, the notches of each pair being located one hundred eighty degrees apart. These notches form ratchet teeth each of which is provided with a straight or radial side and with an inclined side, and all the teeth facing in the same direction and being of equal height. These teeth, as will appear presently, are adapted to coöperate with a pawl and determine the six positions of the controller drum when the latter is shifted in a forward or clockwise direction as viewed in Fig. 2. The disk 42 is also provided with three pairs of notches 46 and 46^a, 47 and 47^a, 48 and 48^a. These notches are also spaced sixty degrees apart, and the notches of each pair are diametrically opposite each other or one hundred eighty degrees apart. These notches form teeth each having a straight or radial side and an inclined side, and all facing in the opposite direction to that in which the teeth on disk 41 face. Furthermore as appears from Fig. 4 of the drawing, the teeth are not of uniform height, but those formed by notches 46 and 46^a and by notches 48 and 48^a are higher than those formed by notches 47 and 47^a, the teeth formed by the latter notches being of the same height as the teeth of disk 41.

Pivotedly secured by pins 49 and 50 to the flange 31 of member 29 and located in the planes of the ratchet disks 41 and 42 respectively, are pawls 51 and 52, the pawls being pivoted intermediate their ends, and the pawl 51 being adapted to engage in the notches of ratchet disk 41, and the pawl 52 being adapted to engage in the notches of ratchet disk 42. The pawls are held yieldingly against the notched edges of the ratchet disks by a coil spring 53 connected at its ends to the two pawls. At the free ends of the two pawls respectively are rollers 54 and 55, which, in this case, are approximately one hundred and eighty degrees apart and project outwardly beyond the teeth of the ratchet disks. The pawl 51, as will appear presently from Fig. 4, normally holds the spindle 16 and the mechanism which is driven thereby against movement in a counter clockwise direction until the pawl is tripped, and the pawl 52 holds the spindle against movement in a reverse direction until tripped.

It will be seen by referring particularly to Fig. 4, that when the controller or controller drum is in an "off" position, pawl 51 engages either notch 43 or 43^a of ratchet disk 41 and consequently these notches may be said to correspond to the "off" positions of the controller. For the same reason notches 44 and 44^a correspond to the "start-

ing" positions of the controller and the notches 45 and 45^a correspond to the "running" positions of the controller. Also when the controller is in "off" position, 5 pawl 52 engages either notch 46 or 46^a of ratchet disk 42, and, therefore, these notches correspond to the "off" positions of the controller, and notches 47 and 47^a correspond to the "starting" positions of the controller, 10 and the notches 48 and 48^a correspond to the "running" positions of the controller. The "off", "starting" and "running" positions of the controller with respect to the notches of the two ratched disks are not indicated 15 on Fig. 4 of the drawing, in order to avoid confusion with the "off", "starting" and "running" positions of the handles which are indicated on Fig. 4.

In order that the pawls may be tripped so 20 as to permit the spindle and drum to be shifted with a snap action after the handle has been moved through a predetermined arc, I have provided tripping means consisting in this instance of a pair of pins 56 25 and 57 which are secured to the flange 28 of member 26 and extend horizontally inward, these pins having at their free ends rollers 58 and 59 respectively, the roller 58 being adapted to engage the roller 54 on the 30 end of pawl 51, and the roller 59 being adapted to engage the roller 55 on the end of pawl 52. The flange 28 of member 26 is also provided with a number of pins 60 35 which project horizontally toward the flange 31 of member 29 over the spring 34 and serve as protecting members for the latter.

The operation of the mechanism above described will now be explained. When the handles and drum are in the "off" position, 40 pawl 51 engages within notch 43 as shown in Fig. 4 or notch 43^a which is displaced one hundred and eighty degrees therefrom. If the handles are turned from the "off" position in a counter-clockwise direction, the 45 tension of coil spring 34 will be increased, and the spindle and parts driven thereby will be held from movement by pawl 51 until after the handles are moved through an arc of approximately sixty degrees or to 50 the "starting" position for the handles, when the roller 58 on the end of the tripping pin 56 engages the roller 54 on pawl 51 and lifts the pawl from the notch 43 or from notch 43^a, depending upon whether the 55 pawls are in the position shown in Fig. 4 or one hundred and eighty degrees from the position there shown. As soon as the pawl is lifted from the notch which it engages so as to clear the tooth formed by said notch 60 the member 29 which carries the pawls is released, and this member, together with the spindle 16 and mechanism driven thereby including the drum 22 are turned with a snap action by the spring 34 to a "starting" 65 position. In this same manner the drum

may be turned step by step in a counter-clockwise direction through all the different positions.

When the handles and drum are in the "off" position the pawl 52 engages either 70 the notch 46 as shown in Fig. 4, or it engages notch 46^a which is displaced one hundred and eighty degrees therefrom. It will be seen, however, that if the handles are shifted in a clockwise direction from the 75 "off" to the "running" position indicated in Fig. 4, although the spring is placed under increased tension by this movement of the handle, the pawl will not be released when the roller 59 carried by the tripping 80 pin 57 engages and depresses the roller 55 carried by the pawl 52 for the reason that the teeth formed by the notches 46 and 46^a are higher than the teeth formed by the notches on disk 41 and the amount which 85 the roller 55 can be depressed by the roller 59 on the tripping pin 57 is not sufficient to lift the pawl clear of the tooth which it engages. Consequently although the handles are shifted in a forward or clockwise direction from the "off" to the "running" position, no movement of the drum can take 90 place and if the handles are released, they will immediately be restored by the spring 34 to the "off" position.

If the handles and drum are in a "running" position (Fig. 4) the pawl 52 will engage either the notch 48 or 48^a, but inasmuch as the teeth formed by these notches are of the same height as the teeth formed by notches 46 and 46^a, even if the handles are moved in a clockwise direction from the "running" to the "starting" position, the pawl 52 cannot be lifted clear of the tooth formed by the notch which it engages. Consequently the drum cannot be turned in a 100 backward direction from a "running" to a "starting" position, and if the handles should be released after being turned backward from a "running" to a "starting" 105 position, they will be immediately returned by the spring 34 to the "running" position. If, however, the drum is in a "starting" 110 position pawl 52 will engage either notch 47 or notch 47^a, and inasmuch as the teeth formed by these notches are shorter than the teeth formed by the other notches of disk 42 and are in fact the same height as the teeth on disk 41, if the handles are moved in a clockwise direction (Fig. 4) from the 115 "starting" to the "off" position, the drum will be moved in a backward direction to the "off" position when the roller 59 on tripping pin 57 depresses roller 55 on the pawl 52 so that it clears the tooth which it 120 engages. It will be seen therefore, from Fig. 4, that the drum may be shifted with a snap action through all the different positions by turning the handles in a counter-clockwise direction, and that it may be 125 130

shifted with a snap action from a "starting" position directly to an "off" position by turning the handles in a forward or clockwise direction, but that it cannot be shifted 5 from an "off" position to a "running" position or from a "running" position to a "starting" position by turning the handles in a forward clockwise direction. It will be seen also that with the operating mechanism 10 which I have provided, the drum will be actuated in a manner such that injury due to arcing will be very small and that the mechanism is practically fool-proof and the controller or starter is in no danger of being 15 injured when in the hands of an inexperienced or careless operator.

I do not desire to be confined to the exact details shown but aim in my claims to cover all modifications which do not involve a 20 departure from the spirit and scope of my invention.

What I claim as new and desire to secure by Letters Patent is:

1. In an operating mechanism for a controller, a controller handle, a spindle, a 25 spring forming a driving connection between the handle and the spindle, a ratchet and pawl mechanism permitting said spindle to be turned in one direction to a plurality of different positions but preventing 30 said spindle to be turned in a reverse direction to certain positions, said mechanism normally holding the spindle against movement, and a member movable with the handle and serving to trip the pawl so as to permit the spindle to be shifted by the spring when the handle has been moved a predetermined amount.

2. In combination, in an operating mechanism for a controller, a controller handle, a controller drum, a spring forming a driving connection between the handle and drum, a ratchet mechanism comprising a pawl and a ratchet disk normally holding 40 the drum against movement, said mechanism permitting said drum to be turned in one direction to a plurality of different positions but preventing said drum to be turned in a reverse direction to certain positions, one of said members of the ratchet 45 mechanism being stationary and the other being movable with the drum, and a tripping device movable with the handle and serving to trip the pawl and permit the drum to be moved from one position to another when the handle is moved through a predetermined arc.

3. In combination, in an operating mechanism for a controller, a controller handle, 50 a spindle adapted to be shifted thereby, a spring forming a driving connection between the handle and spindle, a stationary ratchet disk having notches corresponding to the operative positions of the controller, 55 a pawl movable with the spindle and adapt-

ed to engage the notches of the ratchet disk, and a tripping device movable with the handle and adapted to engage and trip the pawl after the handle has been moved a predetermined distance so that the pawl and spindle 70 may be shifted by said spring from one position to another, said tripping device being effective in one direction of rotation and ineffective in certain positions in the opposite direction of rotation.

4. In combination, in an operating mechanism for a controller, a controller handle, a spindle adapted to be operated thereby, a spring forming a driving connection between the handle and spindle, one end of the 75 spring being operatively connected to the handle and the other to the spindle, a pawl and ratchet mechanism for permitting the spindle to be shifted by the spring with a snap action, said mechanism comprising a stationary ratchet disk, a pawl movable with the spindle and adapted to engage the notches of the ratchet disk, and a tripping device comprising a member which is adapted to release the pawl from a notch of the 80 ratchet disk when the handle has been moved a certain amount, whereby the spring will turn the spindle with a quick movement from one operative position to another, said tripping device being effective in 85 one direction of rotation and ineffective in certain positions in the opposite direction of rotation.

5. In combination, in a controller, a drum, and a quick break operating mechanism for turning the drum with a snap action, said mechanism permitting the drum to be turned in a forward direction to all 90 its operative positions and in a backward direction to a portion only of its positions.

6. In combination, in a controller, a controller drum, and a quick break operating mechanism for the drum comprising a handle, a spring adapted to have energy stored therein by a movement of the handle, and co-operating members which release the drum and permit the spring to turn the same with a snap action after a predetermined movement of the handle, said members permitting the drum to be turned in one direction to all its positions and in the opposite direction to a certain position, but preventing the same being turned in said latter direction to a certain other position.

7. In combination, in a controller, a controller drum, and a quick break operating mechanism which after a predetermined movement of the handle turns the drum with a snap action, said mechanism permitting the drum to be turned in one direction to all its operative positions and permitting the drum to be turned in the opposite direction from a "starting" position to an "off" position only.

8. In combination, in a controller, a drum

- having "off," "starting" and "running" positions, and mechanism for turning the drum with a snap action to all its different positions in a forward direction and permitting the drum to be turned in a backward direction from "starting" to "off" positions only.
9. In combination, in a controller, a controller drum, and a quick break operating mechanism for the drum comprising a handle, a spring forming a driving connection between the handle and drum, and ratchet mechanism for permitting the drum to be released and to be turned by the spring successively through all its positions after the handle is turned successively predetermined amounts in a forward direction, but preventing the drum being turned to certain positions in a backward position.
10. In combination, in a controller, a controller drum, a handle, a spring for transmitting movement from the handle to the drum and adapted to have energy stored therein by a movement of the handle, a pawl and ratchet mechanism controlling the movements of the drum in one direction, a second pawl and ratchet mechanism controlling the movements of the drum in the opposite direction, and means for tripping said pawl in one direction of rotation but for tripping said second pawl only in some of the operative positions of the controller in the opposite direction of rotation.
11. In combination, in a controller, a controller drum, an operating handle, a spring operatively connected to the handle and drum, said spring being adapted to have energy stored therein by a movement of the handle and to shift the drum with a snap action when the drum is released, ratchet mechanism comprising two series of stationary ratchet teeth and two pawls cooperating therewith and movable with the drum, one ratchet mechanism governing the movements of the drum in one direction and the other governing the movements of the drum in the opposite direction, and means for tripping said pawl in one direction of rotation but for tripping said second pawl only in some of the operative positions of the controller in the opposite direction of rotation.
12. In combination, a controller, a controller drum, a handle movable relative thereto, a spring forming a driving connection between the handle and drum, and ratchet mechanisms comprising two series of ratchet teeth and two pawls each of the latter coöperating with one series of teeth, one ratchet mechanism permitting the drum to be moved with a snap action step by step to all its different positions in a forward direction and the other permitting the drum to be moved with a snap action in a backward direction to certain positions only.
13. In combination, in a controller, a controller drum, an operating handle movable relative to the drum, two series of stationary ratchet teeth, and two pawls movable with the drum and each coöperating with one series of teeth, a spring between the handle and drum, and tripping means for said pawls movable with the handle and coöperating with one of the pawls so as to permit the drum to move with a snap action to all its different positions when the handle is turned in a forward direction and coöperating also with the other pawl so as to permit the drum to be moved to certain positions only when the handle is turned in a backward direction.
14. In combination, in a controller, a controller drum, an operating handle, a spring forming a driving connection between the handle and drum, two ratchet mechanisms each comprising a ratchet disk and a pawl, and tripping devices coöperating with said pawls, one ratchet mechanism permitting the drum to be turned with a snap action successively to all its different positions when the handle is moved in a forward direction, and the other ratchet mechanism permitting the drum to be moved with a snap action to certain positions but preventing movement to other positions when the handle is moved in a backward direction.
15. In combination, in a controller, a controller drum, a spindle adapted to turn the drum, a controller handle, a spring having an operative connection with the handle and with the spindle, ratchet mechanisms comprising two series of stationary ratchet teeth and two pawls movable with the spindle, and tripping means for said pawls movable with the handle, the teeth of one series being of uniform height whereby the pawl may be lifted clear of the teeth so that the drum may be turned with a snap action to all its different positions when the handle is moved in a forward direction, and certain of the teeth of the other series being of a height such that the pawl coöperating therewith is prevented from being lifted clear of such teeth when the handle is moved in a backward direction.
16. In combination, in a controller, a controller drum, an operating handle movable relative to the drum, a spring forming a driving connection between the handle and drum, two ratchet mechanisms, one governing the movements of the drum in one direction and the other governing the movements of the drum in the other direction, the teeth of one ratchet mechanism being of equal height and the teeth of the other ratchet mechanism being of unequal height, and tripping means movable with the handle and serving to lift the pawl of one ratchet mechanism from any of the teeth which it engages and to permit the drum to be turned

with a snap action to all its different positions when the handle is moved in one direction, and serving to lift the other pawl from the part only of the teeth which it engages so that the drum can be turned to certain positions only when the handle is moved in the reverse direction.

17. In combination, a controller drum, and an operating mechanism for said drum including means for turning said drum with a snap action, said mechanism permitting the drum to be turned in a forward direction to all its operative positions, and permitting the drum to be turned in a backward direction to a portion only of its positions.

18. A controller, comprising fixed and movable contact members, and means for operating said movable contact member comprising mechanism for imparting a snap action to said movable contact member, said operating means permitting said movable contact to be moved in one direction to any of its operative positions and permitting said contact to be moved in another direction to a portion only of its positions.

19. In combination, a controller drum and

an operating mechanism for said drum including means for turning said drum with a snap action and means for permitting the drum to be turned in a forward direction to all of its operative positions and permitting the drum to be turned in a backward direction a portion only of its positions.

20. In a controller, fixed and movable contacts, means for operating said movable contact relatively to said fixed contact, and means for controlling said operating means to insure the movement of said movable contact with a snap action and for permitting the movement of said movable contact in one direction to all of its operative positions, and permitting said contact to be moved in another direction to a certain position, but preventing movement of said contact in said latter direction to a certain other position.

Milwaukee, Wis., Nov. 22, 1909.

In testimony whereof I affix my signature in the presence of two witnesses.
